UNITED STATES PATENT OFFICE.

JAMES C. McDERMOTT, OF CHICAGO, ILLINOIS.

PIPE-MOLDING APPARATUS.

SPECIFICATION forming part of Letters Patent No. 357,492, dated February 8, 1887.

Application filed February 11, 1886. Serial No. 191,553. (No model.)

To all whom it may concern:

Be it known that I, JAMES C. McDERMOTT, of Chicago, in the county of Cook and State of Illinois, have invented certain new and useful 5 Improvements in Pipe-Molding Machines; and I do hereby declare that the following is a full, clear, and exact description of the invention, which will enable others skilled in the art to which it appertains to make and use 10 the same, reference being had to the accompanying drawings, and to letters of reference marked thereon, which form a part of this specification.

Heretofore it has been customary to make 15 molds for casting iron pipe by packing the cope and drag thereof by hand or hand implements, which requires the exercise of considerable skill and much labor.

The object of my invention is to make the 20 molds, so far as the building of the parts thereof is concerned, entirely by machinery. This I do, expeditiously and thoroughly, by uniting the parts of the flask around a vertical pattern, feeding the sand into the space between the 25 two from the top, and packing the same by means of a cylindrical packer, which as it packs the sand is lifted or forced upward out of said space, substantially as hereinafter described, and as illustrated in the drawings, in 30 which—

Figure 1 is a side elevation of the apparatus embodying my invention. Fig. 2 is a vertical transverse section of the same. Fig. 3 is a detail view showing the lower end of the 35 cylinders surrounding and actuating the packer. Fig. 4 is a detail view showing the top end of the drag and cope. Fig. 5 shows a plan view of the flask, showing the clamps for holding the parts together. Fig. 6 is a detail view 40 showing a side elevation of a sprocket-wheel. Fig. 7 is a plan view of the packer, showing part of the head broken away to expose the friction-rollers. Fig. 8 is a detail view showing the head of the packer in cross-section. Fig. 45 Fig. 9 is a horizontal transverse section of the flask when it is in position for the mold to be built therein. Fig. 10 is a detail view showing a section of the flask in cross-section. Fig. 50 Fig. 11 is a detail view showing the screw-threaded end of the packer, and Fig. 12 is a vertical

transverse section of the lower part of the apparatus embodying my invention.

Reference being had to the drawings, A and A' represent the drag and cope of the flask, having legs *a a* projecting laterally from them, 55 as shown in Fig. 9, and having, when closed and fitted together, the gates *a'*. The parting line of the drag and cope of the flask divides the gates *a'*, so that one half projects from and is made integral with the cope, and the other 60 half projects from and is made integrant with the drag. A cap or cover, B, is provided for the gates *a'*, which has a longitudinal projection, *b*, on its inner surface, which comes to an edge, so that it makes the opening complete to the parting line when the flask is being built.

When it is desired to build a mold in the flask, the parts thereof are placed concentric to and around the vertical stationary pattern 70 C, the basal flanges resting on the flanges of a short cylinder, D, and the upper ends being clamped together by a clamp, *c*, consisting of two arms pivoted to the vertical standard E, surrounding the flask and having their outer 75 ends bolted together, as shown in Fig. 5. The cylinder D is secured to and supported by standard E, and has its lower end flanged. Suitably secured to this flange is the flange on the lower end of the pattern C. When it is 80 desired to build the mold, the cylindrical packer F, which is suitably and concentrically suspended above the flask, is lowered down into the space between the pattern and flask until it reaches a point near the "hub" of the 85 pattern. The sand is then fed to the flask from a conical-shaped hopper located above, surrounding the packer, and secured to the vertical standard in such a manner as to be capable of a limited vertical adjustment, as will 90 be more fully explained hereinafter.

The packer F is provided with a screw-thread or spiral flange around its lower end, so that as the sand is fed to the flask it revolves in such direction as to pack the sand 95 and at the same time lift itself out of the same. The packer F is suspended by means of a suitable rope, chain, or cable, *d*, which passes over a pulley, *e*, having bearings in a frame or bracket extending from or made integrant with 100

standard E, and having a counter-weight, d', on its other end. In order to permit the revolving motion of the packer without twisting the chain or cable d, I provide a circular plate, g, having a central stud projecting up through a corresponding aperture in said head, to the upper end of which said cable or rope is attached. Between the plate g and the inner surface of the head of the packer I place small friction-rollers, thus permitting the revolutions of the packer without generating friction.

In order to revolve the packer when it is desired to build the mold in the manner just explained, I surround it with a drum, G, which is provided with annular flanges h h at its top, and about one-quarter its length above its lower end, which latter is just about on the plane or just above the plane of the mouth of the hopper. These flanges rest on friction-rollers, which have bearings in suitable recesses or channels in rings i, surrounding the drum and secured permanently to the standard E.

Surrounding the drum G just above, or made integrant with the lower flange, h, is a beveled gear, H, which is engaged by a beveled pinion on the end of the drive-shaft J, the contiguous end of which is preferably journaled in the bearings in the standard, and the other in the end of an upright arm of a frame secured to and projecting from said standard. Shaft J is provided with a nest of pulleys on its outer end, which are connected by suitable belting to the main shaft. Arranged diametrically opposite each other on the inner circumference of the drum are the longitudinal flanges k k, and projecting from the head of the packer are the lugs k', which, when the drum turns, are struck by the flanges k, thus carrying the packer around with it, and at the same time permitting the packer to move vertically.

If desired, lugs k' may, as shown in Figs. 7 and 8, have friction-rollers journaled in their ends, and I prefer them this way, as less friction is generated when the packer moves vertically.

I represents a vertical shaft, the upper end of which has bearings in the same frame as has the outer end of the drive-shaft J, and the lower end of which is suitably journaled in a frame projecting horizontally from said standard. It derives motion by means of beveled gearing from the drive-shaft, and has a beveled gear on its lower end, which imparts motion by means of a similar gear to the companion part of clutch K. The clutch K has a longitudinal motion on shaft L by reason of a feather on the same, and its edges and the engaging edges of the companion part are serrated, as shown, so that when brought together they lock. When thus locked, the companion part imparts its motion to the clutch K, and through it moves the shaft L.

The clutch K is reciprocated automatically

by the bifurcated arm m, the extremities of which latter enter the annular groove in the body of said clutch. This arm m is secured to the center of length of a lever fulcrumed about its center to a lug projecting from the standard E. The ends of this lever are connected by means of connecting-rods n n to a crank and double crank, respectively, extending in diametrically opposite directions from the shaft N, journaled in the standard E, and a frame secured to and projecting from the same above the plane of the upper end of the drum, so that its outer end will come about over the vertical center of the packer.

On the end of crank-shaft N is a sprocket-wheel, O, the arms of the bifurcated sprockets of which pass on either side of cable d. When the packer is about leaving the flask, the buttons o on the cable, located with reference to this purpose, catch in the arms of the sprockets and turn the crank-shaft sufficient to actuate the connecting-rods and throw the clutch K into engagement with its companion part, thus imparting motion to shaft L. Sprocket 90.

O is loose on the shaft and can turn freely when the packer is being lowered; but when the packer is raised and the buttons, as explained, reverse the motion of the sprocket-wheel, it turns the shaft N by means of a ratchet, r', snug against its side and fast to said crank-shaft, and pawls on the adjacent face of the sprocket, arranged in such position that they engage said ratchet. When the shaft L is thus set in motion, the cams r r, fast to sleeves 5 thereon, bear against the under side of a cross-bar, r', and raise the same. I make in said cams diametrical slots 2 2, and instead of making them fast to the said shaft L, secure them, by means of bolts 3 3, passing through slots 2 2, to the contiguous eccentric circular flanges 4 4 of sleeves 5 5, fast on said shaft. Thus the cams r can be so adjusted as to increase their eccentricity and raise bar r' higher. Secured to the ends of this bar are vertical studs, which pass through suitable apertures in the lower flange of the pattern, into the space between the same and the flask, where they have secured to them a ring, R. This ring fits the space laterally between the pattern and flask, and as it is forced up packs the sand between it and the lowest point the packer reaches, thus completing the packing of the sand in the flask. Surrounding the studs, supporting the ring between the cross-bar r' and the flanged lower end of the pattern, are coil-springs, which assist the bar to return to its original position. When the mold is made, the next thing to do is to separate the drag and cope for the reception of the core, and preparatory to this the sand on the parting line must be cut or divided. In order to do this, immediately after the completion of the mold I offset the shaft L between cams r r, so as to make an eccentric, r'.

Journaled on the eccentric r' is a pitman, R', the other end of which is pivotally connected

to the links *t*. These links extend vertically up into the bore of the pattern, and have connected to them at one angle the bell-crank *S*, which are fulcrumed at another angle to a boss 5 projecting inward from the pattern, and the remaining angle of each of said bell-crank is pivotally connected to a vertical knife, *s*. There are two knives *s*. Before they reciprocate laterally to divide the sand, as will hereinafter be more fully explained, these knives stand side by side diametrically within said pattern *C*, their inner edgeslapping past each other and their outer edges occupying and filling completely the longitudinal slots placed 15 diametrically opposite each other in the pattern. One rod of link *t* travels vertically within the hollow pattern on one side of the knives and the other rod on the opposite side. Both are so connected to the crank *S*, which 20 pivotally connects them to the knives *s*, that when said links are drawn down they force the knives radially outward through the longitudinal slots in the pattern in directions diametrically opposite each other to the shell of the flasks, thus dividing the sand. These 25 knives are quite thin, so that when they divide the sand they leave but a narrow kerf. This kerf would, when the cope and drag were clamped together, ordinarily leave an opening, 30 which, when the casting was made, would make a fin on the pipe. In order to avoid this, I place a thin strip of metal about the thickness of the knives *s*, conforming to the shape of the meeting edges of the cope and drag, and place it between them when the 35 mold is being made. When the flask proper is put up preparatory to casting, this strip of metal is omitted. The knives have a perfectly horizontal movement by reason of studs *t' t'*. 40 Permanently secured flat against said knives *s*, in lateral alignment with the gates of the flask, are flat strips of metal *S'*, of the same thickness and depth as the said knives, and as long, say, as the blade of caps *B*. The slots in 45 the pattern in register with these strips *S'* are made correspondingly wider to accommodate their passage in and out with the knives. Thus when the said knives are reciprocated to cut the sand the kerf is made wider at the transverse plane of the knives, so that when the 50 flask is finally "set up," ready for the process of casting, the openings made by the caps *B* of the said gates and the blades *b* thereof are connected with the casting-chamber surrounding the core.

The lower end of the packer is beveled, and by vertically adjusting the hopper I can regulate the flow of sand into the flask. This vertical adjustment can be accomplished in many 55 ways; but I prefer the way shown in Fig. 2. By referring to said Fig. 2 it will be observed that this hopper 4 is supported by means of a vertical screw, 5, the threaded portion of which passes through correspondingly-tapped lugs 65 projecting from said hopper, and which has bearings in lugs 6, projecting laterally toward

the hopper from standard *E*. This screw 5 is threaded between its bearings, and by revolving it, through the medium of a handle or other suitable mechanism, the hopper can be adjusted vertically.

The sand may be elevated into the hopper by hand or machinery, either way being possible.

I do not wish to be confined to matters of detail in the construction of my invention, as described and shown, for it is believed these may be departed from without affecting the merits or principle of my invention.

The operation of my machine is substantially as follows: The cope and drag are placed upon the cylinder *D*, so that they surround the pattern *C*, and so that the protuberances projecting from their basal flanges may enter suitable recesses or apertures in the contiguous flanges of said cylinder, as shown in Fig. 4. They are then clamped together, care being first taken to adjust the caps of the gates so that the dividing blades thereof come between the contiguous edges of the projecting portions forming the gates of the flasks, and to adjust between the meeting edges of the cope and drag diametrically opposite the gates a thin strip of metal the thickness of knives *s s*. This operation of the meeting edges of the cope and drag allows for the kerf of the knives, so that afterward, when the flask is ready for use, the sand in the cope and drag is brought close together and forms one complete mold. When the cope and drag are placed in position, as aforesaid, the hopper is supplied with sand, which immediately gravitates down into the space between the pattern and cope and drag. At the same time the packer (which has previously been lowered into said space) is revolved, thus slowly packing the sand as it is poured into it from above. If the sand should flow too fast, the hopper is adjusted vertically, so that the beveled edges of the drum *G* close the mouth of said hopper and limit the flow of sand. When the packer has screwed itself up out of the flask, the button *o* on the cable, by which said packer is suspended, engages the sprockets of the sprocket-wheel *O* and revolves it sufficiently to actuate rods *n n*. These rods shift clutch *K*, so as to impart the motion of shaft *I* to shaft *L*, and shaft *L*, through the medium of cams *r r*, pushes the ring *R* up so as to pack the sand in the lower part of the flask. As the ring *R* withdraws the eccentric *r²* of shaft *L* operates the knives through the medium of pitman *R'*, links *tt*, and bell-crank *S*, so that, passing horizontally through the vertical slots in the pattern, they divide the sand of the cope and drag, as hereinbefore described. The cope and drag are then separated, taken down from around the pattern, again set up around a suitable core, and utilized.

What I claim as new is—

1. In a pipe-molding machine, the combination of the cope *A* and drag *A'*, each hav-

ing legs a and bosses $a' a'$, which form a flask having gates, as set forth.

2. In a pipe-molding machine, the combination of cope A and drag A', having legs a 5 a , gates $a' a'$, cover B, and pattern C, as set forth.

3. The combination, in a pipe-molding machine, of the drag and cope and pattern C, with the packer F, operating as described, 10 shaft L, cams $r r$, cross-bar r' , having vertical studs projecting therefrom, and ring R, substantially as and for the purpose set forth.

4. The combination, in a pipe-molding machine, of the drag and cope and pattern C, 15 with the packer F and ring R, operating as described, shaft L, having eccentric r^2 , pitman R' , links $t t$, bell-crank S, and knives $s s$, substantially as and for the purpose set forth.

5. The combination, in a pipe-molding machine, of the drag and cope and pattern C, 20 of the laterally-reciprocating knives $s s$ and means for operating them, as set forth.

6. The combination, with cope and drag A and A' and pattern C, of the laterally-reciprocating knives $s s$, bell-crank S, links t , and 25 means for operating the same.

In testimony that I claim the foregoing as my own I hereunto affix my signature in presence of two witnesses.

JAMES C. McDERMOTT.
